UNITED STATES PATENT OFFICE

LEE S. CHADWICK, OF SHAKER HEIGHTS, AND MARC RESEK, OF CLEVELAND HEIGHTS, OHIO, ASSIGNORS TO PERFECTION STOVE COMPANY, OF CLEVELAND, OHIO, A CORPORATION OF OHIO

CLEANING DEVICE FOR LIQUID-FUEL BURNERS

Application filed June 2, 1927. Serial No. 195,915.

This invention relates to improvements in the class of devices disclosed and claimed in Letters Patent Nos. 1,487,206 and 1,549,506, granted, respectively, to one of the present 5 applicants, Lee S. Chadwick, on March 18, 1924, and to the other applicant, Marc Resek, on August 11, 1925.

The primary purpose of the present invention is to provide a cleaning device for liquid 10 fuel burners of the class involving a wick and a wick guide, and that will, in one operation, trim the wick, and wipe char or other foreign matter from the wick guide or other parts of the burner.

15 The device is intended for use especially with tubular burners wherein a cylindrical wick is disposed between inner and outer wick tubes, the tubes thus serving as the wick guide. Suitable mechanism is incorporated in the 20 burner for raising and lowering the wick, and in some types of burners wherewith our improved cleaning device is intended to be used, there is automatic wick stop mechanism. An example of such a burner will be found in the 25 second mentioned of the patents above referred to.

Where the term "trim" or "trimming" is used herein, it is intended to mean a removal of the char from the burned portion of the 30 wick, or an actual cutting of the burned part of the wick, or both; and the term "wipe" or "wiping", excepting where otherwise restricted by the context, is employed in its broadest sense and embraces scraping or brushing.

35 Further objects of the invention are to provide a device characterized by any one or more of the features ascribed to the wick cleaners of the above mentioned patents and 40 which incorporates means for wiping one or both of the wick tubes or other burner parts; to provide a relatively simple and inexpensive arrangement for incorporating the wiping means in the wick cleaner; to provide a 45 construction permitting quick and easy replacement and adjustment of the wiping element, together with other and more limited objects which will appear as this description proceeds, reference being had to the accompanying drawings wherein similar reference

characters designate corresponding parts throughout the several views.

In the drawings, Fig. 1 is a side elevation and Fig. 2 is a bottom plan view of our improved cleaning device as constructed for 55 use with a well known type of tubular burner; Fig. 3 is a central vertical section through the device at right angles to the plane of Fig. 1, and through the upper portion of a burner to which the device is applied; Fig. 4 is a detail of the means for securing one end of the wiping element to the body of the device; Figs. 5 and 6 are views similar to Figs. 1 and 2, respectively, of the device as constructed 60 for use with a familiar type of tubular burner involving wick stop mechanism; Fig. 7 is a vertical section, at right angles to the plane of Fig. 4, through the device and the adjacent part of a burner to which it is applied; Fig. 8 is a detail showing the manner of connecting the wiping element to the body of the device in the last mentioned construction; Fig. 9 is a bottom plan view of a modification 65 of the invention; and Fig. 10 is a section on the line 10—10 of Fig. 9.

70 Burners of the type wherewith the present embodiments of the invention are designed for use comprise inner and outer wick tubes 1 and 2, respectively between which a cylindrical wick 3 is guided. Detailed illustration 75 of the burner further than that afforded by Figs. 3 and 7 is deemed unnecessary in this connection since such burners are well known, although it may be explained, briefly, that the tubes 1 and 2 are joined together at 80 their lower ends so as to enclose between them an annular reservoir that is supplied with fuel through suitable connections, and wick raising and lowering means is associated with the structure for adjusting the wick vertically within the space between the tubes. Air distributing members or flame spreaders are 85 employed with burners of the class in question and, in the particular type of burner illustrated in Fig. 3, the flame spreader (not shown) is designed to rest upon an annular flange 4 of a member 5 to which member the flame spreader is adapted to be detachably connected to avoid its being lifted to any appreciable extent by the engagement of the 90

top of the wick with an overhanging flange of the flame spreader when the wick is elevated, all of which will be readily understood by those familiar with the class of burners under discussion. The flange 4 is fixedly connected to the inner wick tube 1 as by having the material of said tube displaced inwardly immediately above and below the periphery of the flange.

10 Our improved cleaning device, as it is designed for use with the burner above described and illustrated in Fig. 3, consists of a body that is designated generally by the reference numeral 10 and that is comprised of upper and lower sections that are preferably constructed of sheet metal, the former section including a top wall 11 and a cylindrical portion 12 adjacent thereto whose lower end is connected through an inclined wall 13 with a larger cylindrical portion 14. The portion 14 fits within a cylindrical wall 15 of the lower body section and is adapted to be connected thereto by any suitable means, as by indenting the material of the overlying parts, as indicated at 16. The lower body section has a bottom wall 17, the central portion of which is inset above the marginal portion 18 thereof, said marginal portion being intended, when the cleaner is applied to a burner, to rest on the annular flange 4 of the member 5 as, by so doing, it properly positions the cleaning device with respect to the upper ends of the wick tubes.

15 The top of the cylindrical wall 15 is flared outwardly and upwardly to form what we shall term the wick engaging flange 20, the same being stiffened by having its outer edge flanged downwardly as indicated at 21. Depending from the underside of the flange 20 is a wick sizer 22 in the nature of a sheet metal ring whose lower edge is false wired at 23 to impart stiffness to the ring and whose upper edge is provided with a plurality of tongues 24 that are extended through slots in the flange 20 and turned over therebeyond, said tongues constituting the means of attaching the wick sizer to the wick engaging flange. The flange 20 is provided with a plurality of tangential slots 25, and the material of the flange along the corresponding sides of all the slots is turned upwardly slightly, as best shown at 26 in Fig. 3, for a purpose that will presently appear. It may be explained that, in burners of the type shown, the tops of the wicks are inclined upwardly and outwardly which accounts for the corresponding inclination of the flange 20.

20 The device as thus far described is substantially the same as the preferred embodiment of the invention disclosed in the above mentioned Patent No. 1,549,506 and in the use of the device for cleaning or trimming the wick and smoothing the end thereof, the device is applied to the burner with the marginal portion 18 of the bottom wall 17 en-

gaged with the flange 14 of the member 5. With the device held firmly against the flange the wick is turned up until its top contacts with the under-surface of the flange 20 and until the outer edge of the wick occupies the angle between said flange and the wick sizer 22. Now, by rotating the device in one direction it will remove the char from the wick, the char being scraped off by the flat sides of the slots 25 and passing through said slots and accumulating in the trough that is formed by the flange 20 and the adjacent inclined wall 13; and when the device is rotated in the opposite direction, the turned-up edges 26 of the slots 25 serve to smooth the wick and impart an even surface to the burned end thereof. Also, a clearly defined edge will be produced by the wick sizer 22. Both these renovations contribute to an even and satisfactory flame.

25 The best results are obtained from the burner only when the upper ends of the wick tubes are free from an accumulation of char or other foreign matter, and to wipe these parts free of such substances while the wick is being trimmed, we employ the means which we shall now describe.

30 A wiping element 28, in the nature of a strip of suitable fabric, such as a piece of lamp wicking, has one of its ends anchored to the bottom wall 17 of the body, the element then being directed beneath a depressed portion 18^a of the marginal portion 18 of said bottom wall and thence upwardly across the outer side of the cylindrical wall 15 and through a slot 29 of the flange 20. The flange 20 is notched at 30 in the radial zone of the slot 29 and the element 28 is engaged over the portion of the flange between said slot and notch and is then passed downwardly inside the wick sizer 22 and outwardly and upwardly about the lower edge thereof and between lugs 31 that extend outwardly from the wick sizer, the upper edge portion of said sizer being flared outwardly, as indicated at 32, to facilitate the threading of the wiping element downwardly through the notch 30. The lugs 31 are preferably struck outwardly from the sheet metal whereof the wick sizer is formed.

35 Journalized within apertures in the lugs 31 are the trunnions 33 of a clamping member 34 which is similar to the clamping element of a suspender buckle, the same comprising angularly related portions, the edge of one of which is provided with teeth 35 that are arranged to bite into the material of the wiping element, and the other of which constitutes a finger piece for swinging the clamping member on its trunnions. The finger piece has a projection 36 at one end that overhangs the adjacent lug 31, and said lug is formed with a square lower corner, as shown at 37, for engagement by said projection thereby to prevent the clamping element from swinging

too far from effective position. When the free end of the wiping element is threaded upwardly between the outer surface of the wick sizer and the clamping member 34 and is drawn taut, the finger piece of said member is thrown upwardly to the position shown in Figs. 1 and 3 thereby to cause the member to securely hold the wiping element in position. As a convenient means of attaching the inner end of the wiping element to the bottom wall 17, said wall is slotted and is formed with teeth on the opposite sides of said slot, as best shown in Fig. 4, and when the end of the element is engaged through the slot and bent squarely beneath the portion 18^a of the bottom wall the teeth imbed themselves within the material of the element and serve to very securely retain the end of the element in place.

Now it will be seen that when the device 20 is operated as above described, the wiping element will brush the upper ends of the inner and outer wick tubes and free them of any foreign matter that may have accumulated thereon.

The device, as illustrated in Figs. 5 to 8, 25 is constructed for use with burners of the aforesaid character but which include the automatic wick stop mechanism described in the above mentioned Patent No. 1,549,506. As shown in Fig. 7, the burner includes among other things, besides the wick tubes 1 and 2, an annulus 38 that is carried by a frame 39 to which latch members 40 are pivoted for interlocking engagement with the 35 type of flame spreader that is designed for use with the present burner, the flame spreader in this instance resting upon the annulus 38 and being detachably connected thereto against independent vertical movement by means of the latch members 40. The only 40 important difference between the present embodiment of our invention and that above described is the omission of the bottom wall 17, said wall being dispensed with in order to provide clearance for the latch members 40. In the absence of the bottom wall (to which the inner end of the wiping element is connected in the previously described embodiment) said end is carried upwardly in- 45 side the body 10 and is engaged outwardly through a slot 43 thereof whose lower edge is formed with teeth 44 that bite into the material of the element when the same is bent sharply downwardly thereover. The same 50 reference characters are used to designate the corresponding parts of the two embodiments.

In Figs. 9 and 10 we have shown a form 55 of the invention that is quite unlike the ones above described. The present construction comprises a circular disk 45 whose marginal portion is inclined upwardly and outwardly to provide a wick engaging flange 46 that has a series of tangential slots 47 for wick 60 cleaning and smoothing purposes. Disposed

beneath the flange 46 is a wick sizer 48 which is constructed of sheet metal and shown as of channel formation, the upper edge of the outer flange being flared outwardly at 49 adjacent the downwardly turned edge portion 50 of the flange 46. A wire ring 51 occupies the angle between the portions 49 and 50 and is soldered, brazed, or otherwise connected thereto and in this manner the parts are securely fastened together.

Secured, as by rivets 52, to the central portion of the disk 45 is a circular wall 53 of a cylindrical member 54 that has its lower end deflected outwardly and then downwardly to provide a cylindrical flange 55 that is interrupted at equally spaced points about its circumference by notches 56 and 57, the notches 56 alternating with the notches 57 and extending through the horizontal or outwardly deflected lower end of the member 54 to a point adjacent the cylindrical wall of said member. Occupying the notches 56 are holders 58 whose upper ends are engaged in depressions 59 of the disk 45, the said holders being soldered or otherwise fastened in place, and within these holders are fitted the backs 60 of brushes 62. The wick sizer 48 is notched on its inner side opposite each of the notches 56 and a holder 61 is secured within each of said notches of the sizer and contains a brush 62 in opposed relation to one of the former brushes 60. Scrapers 65 are located on the corresponding sides of the several notches 57 and the same are conveniently formed of metal strips which have their outer ends secured, as by soldering, to the flange 55 adjacent the slots 57 and their inner ends similarly connected to the holders 58.

When this device is applied to a burner, the flange 55 rests upon the annular member 105 that ordinarily serves to support the flame spreader, and the wick tubes rise between the opposed brushes 60 and 62. The scrapers 65, whose lower edges are flush with the corresponding edge of the flange 55, as will be seen 110 by reference to Fig. 10, serve to remove scrapings that fall from the wick or any other foreign substance that may have accumulated thereon from the flame spreader support, thus insuring the flame spreader resting squarely 115 upon said support, which is important if the flame spreader is to function properly, and the brushes 60 and 62 wipe from the inner and outer wick tubes any char or other foreign matter deposited thereon, while the slotted flange 46 and the sizer 48 serve their respective functions as set out in the foregoing descriptions of the previous modifications.

Having thus described our invention, what we claim is:

1. A cleaning device for use with liquid fuel burners of the class involving a wick and opposed members between which the wick is guided, said device comprising parts that are adapted to be positioned on opposite sides 130

- of the aforesaid members and a trimming part between the former parts that is disposed in operative relation to the burned portion of the wick when said former parts bear the aforesaid relation to the members, and a wiping element extending along the inner side of one of the first mentioned parts and over the trimming part and along the inner side of the other of the first mentioned parts whereby portions of said element are disposed in wiping relation to the aforesaid members when the trimming part is presented in operative relation to the burned portion of the wick.
2. A cleaning device for use with liquid fuel burners of the class involving a wick and opposed members between which the wick is guided, said device comprising parts that are adapted to be positioned on opposite sides of the aforesaid members and a trimming part between the former parts that is disposed in operative relation to the burned portion of the wick when said former parts bear the aforesaid relation to the members, a cleaning element in the nature of a strip of flexible material that is extended across the inner side of one of the first mentioned parts and over the trimming part and along the inner side of the other of the first mentioned parts whereby portions of said element are disposed in operative relation to the aforesaid members when the trimming part is presented to the burned portion of the wick, and means for removably attaching said wiping element to the device.
3. A cleaning device for use with liquid fuel burners of the class involving inner and outer wick tubes, said device comprising a body having radially spaced concentric parts adapted to be disposed on opposite sides of the inner and outer wick tubes and a wick trimming part between said concentric parts for contact with the portion of the wick exposed above the wick tubes, and a wiping element consisting of a strip of flexible material that is extended across the outer side of the inner concentric part, over the trimming part and across the inner side of the outer concentric part whereby portions of the said element are presented in wiping relation to the wick tubes when the trimming part is presented to the exposed portion of the wick.
4. A cleaning device for use with liquid fuel burners of the class involving inner and outer wick tubes, said device comprising a cylindrical body portion adapted to be inserted within the upper end of the inner wick tube, a flange extending outwardly therefrom over the wick tubes, a wick sizer depending from the outer portion of said flange, the flange incorporating wick trimming parts and having openings spaced radially apart on opposite sides of the wick tubes, and a flexible wiping element extending from the bottom of the body portion up-

wardly along the outer side thereof, through said openings in the aforesaid flange, and thence downwardly along the inner side of the wick sizer.

5. A cleaning device for use with liquid fuel burners of the class involving inner and outer wick tubes, said device comprising a cylindrical body portion adapted to be inserted within the upper end of the inner wick tube, a flange extending outwardly therefrom over the wick tubes, a wick sizer depending from the outer portion of said flange, the flange incorporating wick trimming parts and having openings spaced radially apart on opposite sides of the wick tubes, a flexible wiping element having its inner end attached to the body portion, and extending from the bottom of said portion upwardly along the outer side thereof, through said openings in the aforesaid flange, and thence downwardly along the inner side of the wick sizer; and a clamping member carried by the outer side of the wick sizer for holding engagement with the outer end of the wiping element.

6. A cleaning device for use with liquid fuel burners of the class involving inner and outer wick tubes, said device comprising a cylindrical body portion adapted to be inserted within the upper end of the inner wick tube, a flange extending outwardly therefrom over the wick tubes, a wick sizer depending from the outer portion of said flange, the flange incorporating wick trimming parts and having openings spaced radially apart on opposite sides of the wick tubes, a flexible wiping element extending from the bottom of the body portion upwardly along the outer side thereof, through said openings in the aforesaid flange, and thence downwardly along the inner side of the wick sizer, lugs extending outwardly from the wick sizer, and a clamping member pivotally supported by and between said lugs for holding engagement with the outer end of the wiping element.

7. A cleaning device for use with liquid fuel burners of the class involving inner and outer wick tubes, said device comprising a cylindrical body portion adapted to be inserted within the upper end of the inner wick tube, a flange extending outwardly therefrom over the wick tubes, a wick sizer depending from the outer portion of said flange, the flange incorporating wick trimming parts and having openings spaced radially apart on opposite sides of the wick tubes, a flexible wiping element extending from the bottom of the body portion upwardly along the outer side thereof, through said openings in the aforesaid flange, and thence downwardly along the inner side of the wick sizer, bearing members on the outer side of the wick sizer, and a clamping member pivotally supported by and between said bearing mem-

bers and having angularly related parts that are respectively disposed in substantially horizontal and vertical planes when the member is in effective position, the horizontal part having teeth for engagement with the wiping element.

8. A cleaning device for use with liquid fuel burners of the class involving inner and outer wick tubes, said device comprising a sheet metal body incorporating a scraping edge integral therewith for contact with the burned portion of the wick, and supporting surfaces located inwardly and outwardly thereof, the body having slots adjacent the upper edges of said surfaces, and a non-metallic cleaning element extended through said slots and sustained by said surfaces for engagement with the wick tubes.

In testimony whereof, we hereunto affix
our signatures.

LEE S. CHADWICK.
MARC RESEK.
